UNITED STATES PATENT OFFICE

2,480,798

CLOTHESLINE CARRIER

Paul B. Weis, Aurora, Ill.

Application February 23, 1946; Serial No. 649,664

5 Claims. (Cl. 211—119.17)

1

This invention relates to a clothes line carrier and its principal object is to provide a carrier having a clothes line hook which may be lowered from a high position to a low and easy to reach position. As is well known, clothes line hooks are usually located above the reach of the person of average height and as a result a box, chair or the like usually is used to stand on to enable the user to reach the hook and attach the clothes line thereto.

Clothes line hooks are usually located high enough to support the clothes line at a height which will suspend sheets and the like free from the ground.

In accordance with the present invention, the clothes line hook is slidably mounted on a vertically extending guide member secured to a bracket which may be screwed to or otherwise fastened to a clothes pole or other support, the hook being provided with a depending handle or bail whereby the hook may be raised and lowered, and by means of which the hook may be supported in its raised position.

With these and other objects and advantages in view, this invention consists in the several novel features of construction, arrangement and combination of parts hereinafter fully described and more particularly defined in the appended claims.

The invention is clearly illustrated in the accompanying drawing, in which:

Fig. 1 is a side elevation of a clothes pole with one of the clothes line carriers, forming the subject matter of this specification, secured thereto;

Fig. 2 is a front elevation thereof;

Fig. 3 is a horizontal section taken on the line 3—3 of Fig. 1; and

Fig. 4 is a horizontal section taken on the line 4—4 of Fig. 1.

Referring to said drawing, the reference character 5 designates a fragment of a clothes pole to which the clothes line carrier may be secured, as by screws 6 or other fastening means. The carrier is provided with a bracket 7 having an upright bar 8 through which the screws are passed and the end portions of the bar are bent at right angles thereto to provide two arms 9, 10 which are formed with aligned holes. Extending through the holes is a rod or other guide member 11 which projects above and below the arms 9, 10 and is prevented from endwise movement in the holes by cotter pins 12 or the like which extend through holes in the protruding ends of rod 11.

Slidably mounted on the rod 11 is a sleeve 13

formed on one side with a hook 14, around which a clothes line (not shown) may be wrapped or to which it may be fastened. The sleeve is formed with a rearwardly projecting lug 16 which limits the rotation of the sleeve and the latter is also formed with laterally projecting bosses 15, in the ends of which are provided sockets, one of which is seen in Fig. 1 at 15a, in which are held the bent end portions 17 of a handle or bail 18 which extends down from the sleeve and may rest upon the lower arm 10 to support the hook in its raised position. Preferably, the bail is of V-formation and the lower ends of its branches are connected by an open loop 19 which straddles the rod 11 when the bail is placed upon the arm 10.

To lower the hook into convenient position for fastening a clothes line thereto or removing it therefrom, the lower end of the bail is grasped, swung forward to disengage it from the rod 11 and the arm 10, and is then lowered, carrying the sleeve 13 and the hook 14 with it until the sleeve rests on the arm 10, as shown in dotted lines in Fig. 1. The clothes line may then be attached to or detached from the hook, the bail raised to bring the hook to its uppermost position and the open loop of the bail is then moved over the arm 10 and allowed to rest thereon with its open loop straddling the rod.

From the above it is apparent that I have provided a convenient, handy device for lowering a clothes line hook from a high position normally out of reach by a person of average height to a low position easily accessible to the person. The parts are few, easily assembled and principally made of commercial material.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. A clothes line carrier comprising a supporting bracket adapted to be secured to a support, said bracket being formed with upper and lower arms, a rod extending between and secured to the upper and lower arms of the bracket, a sleeve slidably guided upon said rod, said sleeve having a hook thereon and a bail connected to said sleeve and being formed at its lower end with an open loop, whereby the bail may straddle the rod and rest upon the lower arm of the bracket.

2. A clothes line carrier comprising a supporting bracket adapted to be secured to a support and formed with outstanding upper and lower arms at its top and bottom respectively, a rod extending between and secured to said arms, a sleeve slidably guided upon said rod, said sleeve having a hook thereon and a bail pivotally connected to said sleeve and being formed at its lower end with an open loop, whereby the bail may straddle the rod and rest upon the lower 10 arm of the bracket.

3. A clothes line carrier comprising a supporting bracket adapted to be secured to a support and formed with outstanding upper and lower arms at its top and bottom respectively, a rod extending between and secured to said arms, a sleeve slidably guided upon said rod, said sleeve having a hook thereon and a pair of oppositely directed bosses, and a pivoted bail having bent upper end portions engaged in sockets in the ends of said bosses, said bail being formed at its lower end with an open loop, whereby the bail may straddle the rod and rest upon the lower arm of the bracket.

4. A clothes line carrier comprising a supporting bracket adapted to be secured to a support and formed with outstanding upper and lower arms at its top and bottom respectively, a rod extending through said arms, fastening means to secure said rod to the arms, a sleeve slidably guided upon said rod, said sleeve having a hook thereon and a pair of oppositely directed bosses and a pivoted bail having bent upper edge por-

tions engaged in sockets in the ends of said bosses, said bail being formed at its lower end with an open loop, whereby the bail may straddle the rod and rest upon the lower arm of the bracket.

5. A clothes line carrier comprising a supporting bracket adapted to be secured to a support and formed with outstanding upper and lower arms at its top and bottom respectively, a rod extending between and secured to said arms, a sleeve slidably guided upon said rod, said sleeve having a hook thereon and a pair of oppositely directed bosses and a pivoted bail having bent upper end portions engaged in sockets in the ends of said bosses, said bail being formed at its lower end with an open loop, whereby the open loop may straddle the rod and rest upon the lower arm of the bracket.
